UNITED STATES PATENT OFFICE.

EDOUARD FOUGEIROL, OF LES OLLIÈRES, FRANCE.

WINDING-MACHINE FOR COTTON AND OTHER TEXTILE THREADS.

1,056,899.

Specification of Letters Patent. Patented Mar. 25, 1913.

Application filed May 3, 1911. Serial No. 624,775.

To all whom it may concern:

Be it known that I, EDOUARD FOUGEIROL, a citizen of the Republic of France, residing in Les Ollières, Ardèche, France, have invented certain new and useful Improvements in Winding-Machines for Cotton and other Textile Threads, of which the following is a specification.

The present invention relates to a machine with a fixed winding frame for winding cotton, linen, ramie, and practically all textile threads, into "cheeses," cops or the like.

Threads which are to be used for weaving, usually come to the weaver in hanks, and are rewound by him into cops or "cheeses" for use in his loom. These "cheeses" or weft cops cannot generally be formed from the threads as they come directly from the hanks for several reasons, of which the two principal are—first, that in order to form these "cheeses" or cops the thread ought to be under a nearly constant tension; second, that the arrangement should permit of the thread being unwound rapidly without interruption. With rotating winding frames the first condition cannot be realized on account of the threads catching, and the second condition cannot be realized since the winding must be done slowly, and it would seem that two operations are necessary for constructing these "cheeses" or cops, the first consisting in unwinding the hanks and winding the thread in auxiliary bobbin frames, the second in unwinding these auxiliary bobbins and winding the thread on any kind of spool, such as ordinary cylindrical spools, split cylinders of the kind known as Alexander bobbins, or cop frames of other design.

The present invention provides a machine having a fixed winding frame, and wherein the rapid unwinding of the hanks and the winding of the unwound thread directly on any kind of bobbin or cop frame under constant tension, may take place at one time. The fixed winding frame allows the thread to be unwound without tension, since only the thread is in motion and the thread after being unwound can be carried to the bobbins for forming the "cheeses" or to the machine for forming the cops under a constant tension, which may have any suitable value. The winding can take place at a high speed, since the thread is unwound without tension.

In the embodiment chosen for illustration,

bobbins with split cylinders are shown as used for making the "cheeses."

In the accompanying drawings—Figure 1 is a side view, and Fig. 2 is an end view 60 of the machine; Fig. 3 is a view on an enlarged scale of a fixed winding frame; Figs. 4 and 5 are detail views.

The fixed winding frames A are mounted on the bearings C, through which a spindle 65 X, Y, Z passes carrying on one side a ring D and on the other side a pulley E. The pulley is rotated by a cord F from a pulley G, mounted on the shaft H. The thread I unwinds from a fixed frame A and at the 70 same time turns with the ring D and passes down through a centrally disposed guiding eye J and thence to a bobbin frame provided with split cylinders K. In Fig. 2 the fixed frame is shown in the usual octagonal form 75 and the device L for stretching the thread is also illustrated. Loose pulleys E¹ may be arranged beside driving pulleys E so that mechanism may be put out of operation. Upon a tapered part Y, Z of the pulley 80 spindle X, Y, Z is arranged a socket R which is secured in position on the spindle by means of a fastening nut S. To the socket R is attached the web T of the revolving unwinding ring D. The foregoing 85 parts, (pulley E, spindle X, Y, Z and ring D) are rotated together by means of the belt or cord F. The bearing in which this spindle revolves is formed in the winding-frame holder B. A turned iron rod O¹ fixed 90 upon the frame-work of the machine is fitted into the bore O of the winding frame-holder, and the latter is provided with a depending part Q which bears laterally on a guide rod M and prevents the frame-work B from turning. The winding frame-holder B sliding 95 on the rod O¹ and guide rod M together with the spindle, winding frame and unwinding ring D can easily be taken off and set again into position.

The winding frame A remains at rest while the hank thread is unwound, instead of being turned by the unwinding of the thread as in unwinding machines used heretofore, but it should preferably be arranged 105 so that it can be rotated for the purpose of locating the end of the hank threads thereon, as when a thread breaks. For this purpose the winding frame-holder B has a cylindrical exterior and carries the hub of the 110 winding frame thereon. The winding frame remains at rest while the thread is un-

wound, but by taking hold of the winding frame it can be revolved on the holder B.

The machine is shown as provided with three winding frames, but obviously any desired number can be used.

5 What is claimed is:—

1. In a machine of the character described, the combination of a hank-frame, a support for said frame, comprising a round 10 bar, a sleeve upon which said frame is mounted, said frame being normally stationary thereon but adapted to be manually rotated, said sleeve being slideable on said bar to move said frame into and out of place 15 in the machine, an arm on said sleeve and a bar against which said arm rests to prevent rotation of said sleeve on said round bar, a rotary spindle in said sleeve, a disk upon said spindle for unwinding threads from 20 said frame, and means for winding the unwound thread.

2. In a machine of the character described, the combination of a hank-frame, a support for said frame, comprising a round 25 bar, a sleeve upon which said frame is

mounted, said frame being normally stationary thereon but adapted to be manually rotated, said sleeve being slideable on said bar to move said frame into and out of place in the machine, an arm on said sleeve and a 30 bar against which said arm rests to prevent rotation of said sleeve on said round bar, a rotary spindle in said sleeve, a disk upon said spindle for unwinding threads from 35 said frame, and means for winding the unwound thread, said means comprising a split winding drum for winding the unwound thread in the form of "cheeses," and tension means intermediate said unwinding means and winding drum, whereby said thread may 40 be removed at high speed and under constant tension.

In witness whereof, I have hereunto signed my name in the presence of two subscribing witnesses.

EDOUARD FOUGEIROL.
